UNITED STATES PATENT OFFICE.

JOHN L. FRUIN AND WILLIAM J. WALKER, OF CHICAGO, ILLINOIS.

PLUMBER'S FITTING.

SPECIFICATION forming part of Letters Patent No. 689,045, dated December 17, 1901.

Application filed May 16, 1901. Serial No. 60,533. (No model.)

To all whom it may concern:

Be it known that we, JOHN L. FRUIN and WILLIAM J. WALKER, citizens of the United States, and residents of Chicago, county of Cook, and State of Illinois, have invented certain new and useful Improvements in Plumbers' Fittings for Use in Plumbing Systems, of which the following is a specification.

This invention relates to fittings for use in plumbing systems, the same being more especially adapted for use in association with a plumbing system forming the subject-matter of our former application for patent on a plumbing system, Serial No. 712,911, filed April 15, 1899, allowed April 26, 1901. The plumbing system referred to as forming the subject-matter of the said application comprises a vertical combination waste and vent pipe, open to the atmosphere at its upper end, a re-
20 vent-pipe extending parallel therewith and also open to the atmosphere at its upper end, and suitable branch connections located at intervals along said pipes, said connections including as an element thereof a special
25 form of branched fitting adapted to be included in the waste-pipe, said fitting having an integral branch, which latter is tapped laterally by the waste-pipe from the adjacent fixtures.

30 Our present invention resides in a special construction of fitting designed to be located at the lower end of the revent-pipe of such a system as we have described, said fitting having its main tubular section integrally offset
35 at its lower end in a downwardly-slanting direction and thence extending parallel with the main tubular section to form a vertical union with the branch of the waste-pipe fitting in such a manner as to conduce to an
40 economy of space required between the waste and revent pipes, and further constructed in such a manner as to facilitate the venting and siphon-breaking function of the revent-pipe with a minimum of friction and obstruc-
45 tion to the air or gases flowing therethrough.

Our invention is illustrated in the accompanying drawings, in which—

Figure 1 is a view in side elevation, broken away, of a plumbing system having vertical waste and revent pipes and showing our invention applied thereto; and Fig. 2 is a detail in side elevation of a fitting constructed

in accordance with our invention and adapted to connect the lower end of the revent-pipe with the waste or soil pipe.

55

In the drawings, A represents a vertical waste or soil pipe, which is usually located in one of the walls or partitions of a building, the same being open to the atmosphere at its upper end above the roof of the building, 60 said waste-pipe thus having a venting function relatively to the several fixtures discharging at various levels thereto.

B indicates a revent-pipe located adjacent to and parallel with the waste-pipe A and 65 having its upper end either extending above the roof and open to the atmosphere, like the pipe A, or preferably having its upper end tapping the upper portion of pipe A and communicating with the atmosphere through 70 the latter in the manner shown.

In the pipe A, at distances apart corresponding to the several floors of the building, are located a series of fittings C, constructed as shown in the pending application hereinabove referred to and each comprising, essentially, a straight portion c, which when the fitting is in place forms a continuous part of the waste or soil pipe, and an upwardly-inclined branch c', formed integral with the 80 straight portion c, and said branch c' being provided with a lateral aperture c², into which may be tapped the drain-pipe from an adjacent fixture.

75

Between the several sections of the revent-pipe B are interposed a series of fittings which are designated as an entirety by D, each of which comprises a straight portion d, which when the fitting is in place forms a continuous part of the revent-pipe B, and a pair of 90 oppositely-disposed integral lateral branches d' and D², connected with the straight portion d in a particular manner, all as herein-after more fully described. The straight portion d of the fitting is provided at its upper 95 end with a hub or enlarged collar d³, which is adapted to receive the adjacent lower end of the superposed revent-pipe section and to be connected therewith by a suitable lead-called joint, the lower end of the fitting entering a 100 similar collar d⁴ on the upper end of the subjacent revent-pipe section. The integral branch d² taps the fitting near the upper end thereof, said branch being extended out-

wardly a short distance and then curved downwardly parallel with the waste and revent pipes, its lower end being suitably calked into the upper end of the branch c' of fitting C.

- 5 The opposite lateral extension d' of the fitting D is adapted to be connected through suitable pipes E and F and elbow G with the upper bend of a trap H in the drain-pipe I, leading from an adjacent fixture, as a bath-tub 10 or bowl K, in order to vent said trap and prevent the siphoning thereof in a well-understood manner.

Referring now more particularly to the special construction of fitting forming the 15 subject-matter of our present invention and which is shown in isolated detail in Fig. 2 of the drawings, it will be observed that the straight principal body portion d of the fitting is integrally offset at its lower end and 20 thence extends parallel with the main section of the fitting downwardly, as shown at d^2 , to form a vertical union with the curved branch of the soil-pipe fitting C. Preferably, also, this fitting is supplied with the lateral 25 branch d' , hereinabove described in connection with the fittings interposed between the sections of the revent-pipe; but this latter feature does not constitute an essential element of our invention.

30 Fitings occupying the general relation hereinabove described to the other parts of the system have heretofore been used in the revent-pipes of plumbing systems; but so far as we are aware no such fitting has ever been 35 constructed provided with an integral downwardly-slanting offset at its lower end adapted to form a vertical union with a suitable receiving member or branch of the soil-pipe. The construction described effects 40 a material economy of space between the revent and waste pipes as compared with the constructions now in use and comprises in a single integral structure what has heretofore been made in a plurality of connected parts.

45 In such old fittings as heretofore made in commercial forms for general use wherever applicable in a plumbing system no regard has been paid, so far as we are aware, to a proper conjunction of the branch or branches 50 with the main member of the fitting in order to effect the ventilating function therethrough with the minimum of friction, and consequently with a maximum efficiency. The lateral extensions of the fitting have 55 heretofore been joined to the main body without regard to the direction of the air-current

flowing therethrough, the extensions in all fittings of this class with which we are acquainted joining the main body on straight lines at right angles thereto or on downwardly-extended curves which are opposed in direction to the direction of flow of the air, thereby necessitating the passage of the air around a sharp edge or corner in the fitting and to that extent decreasing its efficiency. 60 It will be observed that in our present improved fitting we lead the extensions d' and d^2 into the central stem or body d on upwardly-extending curves which are so related to the direction of flow of the air-current as to offer no obstacles in the way of sharp edges or corners for the air to get around. 65

A fitting for a revent-pipe formed and constructed as hereinabove described effects a 70 marked economy in cost of manufacture as compared with fittings of this type now in use. By reason of its integral character it effects an economy of space and enables the elements of the stack to be set much closer 75 together, and by reason of the mode of joining the lateral extensions to the main central body in such a way as to avoid all interference with the air-current therethrough the efficiency of the revent-pipe, and consequently the sanitary value of the entire system, is enhanced. While this fitting is well adapted for use in a system such as that set forth in our former application referred to, it is by no means limited to use in connection 80 with such a system, but may advantageously be employed in a revent-pipe in any other system or relative construction or arrangement of reventing where such a pipe is employed to insure the safety of the traps of 85 the several fixtures from being siphoned.

We claim as our invention—

A fitting adapted to be applied to the lower end of a revent-pipe of a plumbing system, said fitting comprising a main tubular section which at its lower end is integrally offset in a downwardly-slanting direction, and then extends parallel with the main tubular section to form a vertical union with one member of a suitable fitting interposed in the 100 soil-pipe, substantially as described. 105
